UNITED STATES PATENT OFFICE.

FRANK A. BLAIN, OF FORT WORTH, TEXAS.

SAW-FILING MACHINE.

No. 919,814.

Specification of Letters Patent. Patented April 27, 1909.

Application filed August 20, 1907. Serial No. 389,345.

To all whom it may concern:

Be it known that I, FRANK A. BLAIN, a citizen of the United States, residing at Fort Worth, Texas, have invented certain new and useful Improvements in Saw-Filing Machines, of which the following is a specification.

This invention relates to machines for filing the saws of gins or linters, and the object is to improve the construction and operation of the machine described in the patent to John M. Beaver, No. 845,843, issued March 3, 1907, the improvements being accomplished by new elements which reduce the number of parts and which make the operation simple.

Other objects and advantages will be fully explained in the following description and the invention will be more particularly pointed out in the claims.

Reference is had to the accompanying drawings which form a part of this application and specification.

Figure 1 is a broken plan view of the machine. Fig. 2 is a broken plan view in section, illustrating the gear shifting mechanism. Fig. 3 is an end elevation of the machine. Fig. 4 is a vertical section along the line $x-x$ of Fig. 1. Fig. 5 is a detail view of the tripper for causing the driving belt to be shifted 30 to an idle pulley. Fig. 6 is a side elevation of the cog wheel which is intermittently actuated to effect the feeding of the saws. Fig. 7 is an end elevation of the adjustable eccentric head or bearing for taking up the slack of the sprocket chains of the filer.

Fig. 8 is a detail view of the eccentric bearing shown in Fig. 7. Fig. 9 is a detail view of the threaded clamp which engages the feeding screw. Fig. 10 is a side elevation of 40 the frame which spaces the filers apart.

Figs. 11 and 12 are detail views of the devices which make the spacing frames adjustable toward and from each other. Fig. 13 is a detail view of the adjustable bearing for 45 which shafts of different lengths may be mounted in the machine. Fig. 14 is a cross section, taken on the line $y-y$ of Fig. 13. Fig. 15 is a plan view of one of the filers. Fig. 16 is a side elevation of the same. Fig. 17 is a 50 detail view of the devices for vertical adjustment of the filers.

Similar characters of reference are used to indicate the same parts throughout the several views.

This machine is provided with a frame 55 which consists of end upright pieces 1 and 2, top beams 3 and 4 connecting the end frames 1 and 2, and bottom beams 5 and 6 connecting the end frame pieces 1 and 2. A further pivoted frame 7 is hinged to the 60 lower part of the main frame for mounting the gangs of saws. A rocker-shaft 8 is mounted on the main frame and provided with cranks 8' and link rods or bars 9 are pivotally connected to the cranks 8' and 65 pivotally connected with the frame 7. By means of this hinged frame the gang of saws may be mounted in position for operation and may be swung outward for feeding purposes.

70 Means are provided for holding gangs of saws of different dimensions. A hollow shaft, or a shaft in which a recess is drilled, is cut or slotted into four parts as far as may be necessary for adjusting purposes and the 75 exterior of the four parts threaded. The shaft 10 is thus threaded and divided into four parts and a collar 11 is mounted on and engages the threads of the shaft. The gang shaft 12 is inserted in the shaft 10 and 80 clamped therein by screwing the collar 11 toward the end of the shaft 10. The four parts of the shaft 10 are flared at the outer ends so that when the collar 11 is screwed toward the end of the shaft the four parts 85 are clamped on the gang shaft 12. The gang shaft 12 may be inserted more or less in the shaft 10 according to its length. A ratchet wheel 13 is mounted on shaft 10 and is actuated by a pawl 14. The pawl 14 is actuated 90 from the main driving shaft 15.

Means are provided for swinging the saw shaft or mandrel in position for filing the saws and for swinging the saw mandrel out of filing position automatically, throwing the filing gear out of operation, shifting the saw filers the space of one saw, and throwing the filing gear back into operative position, all without the attention of an operator. The order in which these operations take place is as follows: A tripper carried by the saw mandrel throws the filing gear out of operation, the same operation starts a cog wheel to turning. This cog wheel carries a cam which strikes a pin 95 on a slide bar which causes the mandrel to swing outward, while the mandrel is swung outward, the said cog wheel carries pins 100 105

which actuate a screw shaft to move the filers the space of one saw from another. The said cam then strikes a pin on a slide bar to swing the saw mandrel back into filing 5 position, and in immediate succession said cam strikes a pin on another slide bar to start the filing gearing to operation and at the same time moves the tripping roller back to the front of the machine to be tripped on 10 the completion of the next revolution of the saw mandrel.

A tripper 16 is mounted on the saw mandrel 17 by means of a set screw 18. The tripper is provided with a spring-actuated 15 rod 19 which engages a roller 20 which is mounted on the end of a shifting slide bar 21. It will be understood that the saw mandrel must make a complete revolution between each tripping operation so that all 20 the teeth of one saw are sharpened by the filers before a shift of the mandrel is made. The object in making the rod 19 yielding is that when the mandrel 17 is swung back into position for filing the rod 19 will strike 25 the end of the roller 20 and yield back into the collar 16 instead of breaking or injuring the roller. The bar 21 actuates a crank 22 and carries an upstanding pin which is engaged loosely by the crank 22, as shown in Fig. 1. 30 The crank 22 actuates a vertical shaft 23. Shaft 23 carries a crank 24 rigid therewith. Crank 24 loosely engages a pin on a slide rod 25. The slide rod 25 carries a belt shifter 26. The slide rod 25 is provided with suitable 35 bearings. The belt shifter 26 shifts a belt from the fast pulley 27 to a loose pulley 28 which pulleys are mounted on the main driving shaft 15. The same shifter also shifts the belt from the loose pulley to the fast 40 pulley. Spring 31 which is attached to the machine frame and to the slide bar 21 moves said slide bar when said slide bar is released from the locking pawl 29. When 45 the tripper rod 19 strikes the roller 16, the slide bar 21 is shifted sufficiently to be released from the pawl 29.

Simultaneously with the last operation a pinion 34 is locked to the loose pulley 28 by means of a clutch which is formed of one jaw 50 on the hub of the pinion and one jaw on the hub of the loose pulley. This operation is accomplished by reason of the fact that the pawl 29 which is rigid with a vertical rocker-shaft 30 is released from the bar 21 and may 55 be rocked. An arm 36 is rigid with the rocker-shaft 30 and this arm carries a yoke which engages the hub 37 of the pinion 34 by which the pinion 34 may be moved axially on the shaft 15. It will be understood that 60 pulley 28 and pinion 34 are both loosely mounted on the shaft 15 and that the pinion 34 stands normally in mesh with cog 35. While the pinion 34 is not locked to the loose pulley 28, the running of the pulley 28 65 accomplishes nothing, but as soon as the

pulley 34 is locked to the loose pulley, the driving belt on loose pulley drives also pinion 34. The pulley 34 is locked to the pulley 28 by the action of a spring 90 which is attached to the machine frame and to an arm 70 91 on the rocker-shaft 30. As soon as the pawl 29 is released from bar 21, the spring 90 turns the shaft 30 and locks the pinion 34 to loose pulley 28. The pinion 34 then drives the cog 35. When cog 35 begins to 75 turn, a cam 38 on cog 35 at once engages a pin 39 on sliding bar 40 and moves this bar toward the front of the machine. The bar 40 is pivotally connected to a crank 41 which is rigid with the shaft 8. The bar 40 80 thus rocks the shaft 8 and this operation through cranks 8' and link bars or pitmen 9 throws the saw mandrel frame forward and moves the saws out of contact with the filers. The wheel 35 continues to turn and in quick 85 succession the pins 42 which constitute face cogs on the face of cog 35 engage the pinion of star wheel 43. This pinion 43 is revolved by the pins 42 and turns the screw shaft 44 to the filers the space of one saw from another, as hereinafter explained. The wheel 35 continues to revolve and the same cam 38 engages the pin 45 on bar 40 and moves this bar toward the back of the machine and thus 90 rocks the shaft 8 to return the gang of saws 95 back to operative position. Before the cam 38 finishes this operation, this same cam engages a pin 46 on a slide bar 47 to throw the filing gear into operative position. The vertical rocker-shaft 23 has an arm or crank 48 100 rigid therewith and a link bar 49 is pivotally connected with bar 47 and with arm 48. The vertical rocker-shaft 23 is thus rocked and the arm or crank 48 shifts the driving belt back to the fast or driving pulley and at 105 the same time the tripping slide bar 21 is moved to the front of the machine by means of the arm or crank 22. The slide bars 21 and 47 move simultaneously in opposite directions. The bar 21 is actuated by the 110 spring 31 to throw the filing gear out of operation and the bar 47 is actuated by the wheel 35 to throw the filing gear into operation. The gang of saws is brought to filing position almost at the same time (but 115 slightly prior,) as the driving belt is shifted to the fast or driving pulley. When the last saw on the gang of saws has been filed a stud-bolt 92 on one of the filer frames will trip the dog 33 and release the lever 32. This lever 120 32, being rigid with the vertical rocker shaft 30, holds this shaft to a very limited rocking motion while the lever 32 is locked by the spring dog 33. This rocking motion is sufficient to allow the shaft 30 to lock and unlock the clutch of pinion 34 and loose pulley 28, but not sufficient to move the pinion 34 out of mesh with the cog 35. But when the dog 33 releases the lever 32, the spring 90 rocks the shaft 30 sufficient to move the 125 130

pinion 34 out of mesh with cog 35. Consequently the machine will stop after the last saw on the mandrel has been sharpened.

The machine is provided with means for sharpening the saws. The drawings show two filers which are duplicates in construction and operation. The filers are driven by the main driving shaft 15. Sprocket wheels 50 are mounted on shaft 15 and sprocket wheels 51 are mounted on shafts 55 which are provided with journal bearings 52. The journal bearings 52 are rotatable by means of heads 53 which are integral with the journal bearings 52. The openings through the journal bearings 52 for the shafts 55 are eccentrically disposed in the journal bearings. The heads 53 and the journal bearings 52 are made stationary by means of the yokes 56 and nuts 57. The yokes may be released and the journals set with the shafts 55 located at the proper distance to take up the slack of the sprocket chains 50. The shafts 55 carry crank wheels 58 which drive the filers. Pitmen 59 engage the crank wheels 58 and are pivotally connected to reciprocating blocks 60 which move in stationary blocks 61. The reciprocating blocks 60 have upstanding ears 62 to which the pitmen 59 are pivotally connected. The reciprocating blocks 60 carry the filers. A pair of file carrying arms 63 are pivotally mounted on a vibrating block 64 by means of pivot bolts 65. The block 64 is pivotally mounted on the block 60 by means of a pivot bolt 66. The block 64 has a reduced upwardly projecting portion from which projects an arm 67. A rod 68 runs through arms 63 and through the upwardly projecting portion of block 64 and a spiral spring 69 is mounted between each arm 63 and a nut 70 on the rod 68. The rod 68 guides the arms 63, causing them to vibrate in a horizontal plane. A bracket 71 is attached to block 60 and provided with upwardly projecting ears 72. A guide rod 73 runs through the ears 72 and through the arm 67 to cause block 64 to vibrate in a horizontal plane and a spiral spring 74 is mounted on the rod 73 on each side of the arm 67 and between said arm and each ear 72. The block 64 has vibratory motion on the block 60, the arm 67 receiving the rod 73 loosely. The arms 63 receive the rod 68 loosely so that the arms have vibratory motion on the block 64, the arms 63 being pivotally mounted on said block. The arms 63 carry files 75. At the outer ends the tips of the files run through the points of the arms 63 and the inner ends of the files are secured to the arms by clamps 76. The arms 63 are crossed in operation for filing each saw tooth on each side thereof. The block 61 which carries the filer is adjustable so that the files may be set at different heights. The entire filing mechanism is mounted on a frame piece or base 77 which has upwardly

projecting bearings 78. The block 61 is pivotally mounted in the bearings 78 by a downwardly projecting lug or lip 79 and a rocker-shaft 80 runs through the lip or lug 79 and through the bearings 78. A flange 81 is formed on the block 61. A stud 93 is mounted rigidly in base 77 and a sleeve 82 having flanges at both ends is screwed down on the stud 93, the flange 81 having a slot to receive the sleeve 82. A spiral spring 74 is mounted on the sleeve 82 between the upper flange of said sleeve and the flange 81. The sleeve 82 may be screwed down more or less on the stud 93 and the spring 74 will hold the flange 81 down on the lower flange of the sleeve. The block 64 is thus held at the desired height by the flange 81. The object of this vertical adjustment is to adapt the files to the saws on the mandrel.

The two filers are held at fixed distances apart so that each filer will file one-half of the saws on a gang of saws. The two filers are connected together by a telescopic frame composed of two rods at the top, a frame piece at the bottom and connecting side pieces. The bars 77 are provided with tracks 94 mounted on the frame pieces 3 and 4. These bars 77 have downwardly projecting ears 84 and the telescoping rods 85 are connected with the ears 84. This connecting frame has upright portions 86 which are connected to the bases 77 and which are formed integral with telescopic base pieces 87. The connecting frames have bearings 88 which loosely engage the shaft 15. The two parts of the base 87 are connected by slabs 89 which may be clamped on the base pieces by suitable nuts. The object of making the connecting frame telescopic is to make the frame adjustable to saw mandrels of different lengths.

The teeth on each saw are fed to a filer successively by the pawl 14 and ratchet 13. The pawl is actuated by an eccentric 95 which is mounted on shaft 15. Every time the shaft 15 turns once, the pawl 14 moves the saw one tooth and the gearing of the filer is adapted to make the files strike each tooth four times. The filers travel on the screw 44 which is journaled in brackets 96. The filers are connected to the screw 44 by a separable yoke 97 which is threaded to receive the screw 44. The yoke 97 is clamped on the screw 44 by means of a bolt 98 and a nut 99. The yoke engages the adjacent rod 85 and is held rigidly thereto by a set screw 100. The yoke 97 is clamped on the screw 44 at the beginning of the sharpening of a gang of saws. As the saws are sharpened the filers move along, being carried by the screw, toward the cog 35. As the last saw is finished the stud bolt 92 strikes the tripping dog 33 and unlocks the lever 32, as heretofore explained, and stops the machine from running. The yoke 97 may then be released.

and the filers moved back to their starting point. A driving belt 101 is shiftable from pulley 27 to pulley 28 and vice versa and this belt may be driven by any suitable power.

Having fully described my invention, what I claim as new and desire to secure by Letters Patent, is,—

1. In a saw-filing machine; a traveling platform, a reciprocating block mounted in said platform, a vibratory block mounted on said reciprocating block, file carrying arms pivotally mounted on said vibratory block, and means for guiding said arms in their vibratory motion in a plane parallel to the plane of said vibratory block during operation.

2. In a gin saw-filing machine; a reciprocating block, a vibratory block mounted on said reciprocating block and provided with an arm projecting therefrom, a guide for guiding the arm in its vibratory motion, file carrying arms on the vibratory block adapted to vibrate in a plane parallel to the plane of said block, and means for guiding said arms in their vibratory motion.

3. In a saw filing machine; a reciprocating block, a vibratory block mounted on said reciprocating block and provided with a projecting arm, a bracket mounted on said reciprocating block and provided with upstanding ears, a rod run through said arm and through the ears of said bracket, a spring mounted on each side of said arm and between said ears, file carrying arms pivotally mounted on said vibratory block and adapted to vibrate in a plane parallel to the plane of said vibratory block, and means for guiding the vibrations of said arms.

4. In a saw filing machine provided with a saw mandrel support and means for rotating said mandrel step by step; a reciprocating block, a vibratory block carried by said reciprocating block, said vibratory block having an upwardly projecting member, file carrying arms pivotally mounted on said vibratory block and projecting on each side of said upwardly projecting member, a rod running through said arms and through said upwardly projecting member and provided with nuts on the ends thereof, and springs between said nuts and said arms on said rod.

5. In a saw filing machine provided with a saw mandrel support and means for rotating said mandrel step by step; a traveling platform, a guide block pivotally mounted on said platform, a reciprocating block mounted in said guide block, file carrying arms operatively mounted on said reciprocating block, and means for adjusting the free end of said guide block and holding the same yieldingly

at different vertical adjustments whereby said arms will direct files to saws at different heights.

6. In a saw filing machine provided with a saw mandrel support and means for rotating said mandrel step by step; a traveling platform, a guide block pivotally mounted on said platform and provided with a laterally projecting flange, a reciprocating block mounted in said guide block, file carrying arms operatively mounted on said reciprocating block, a screw threaded stud mounted in said platform, a sleeve moving loosely through said flange and provided with head flanges at both ends and screwed down on said stud, and a spring mounted on said sleeve between the upper head thereof and the flange carried by said guide block.

7. In a saw filing machine provided with a main frame and a frame pivoted thereto for carrying a gang of saws; a filing mechanism movable on said frame, a shifting screw shaft connected with said filing mechanism and provided with a pinion, a main driving shaft, a fast pulley mounted on said shaft for driving the filing mechanism, a second pulley and a pinion loosely mounted on said main driving shaft, means for locking said loose pulley and said pinion together, a belt shifter, a belt, a cog wheel normally in mesh with said loose pinion and provided with pins for actuating said screw-shaft pinion, and means for automatically actuating said belt shifter to shift said belt from the fast pulley to the loose pulley and simultaneously locking said loose pulley to said loose pinion whereby said cog wheel commences to revolve.

8. In a saw filing machine provided with a main frame and a frame pivoted thereto for carrying a mandrel for a gang of saws; a filing mechanism movable on said main frame, means for shifting said filing mechanism step by step, a slide bar carrying pins near each end thereof and operatively connected with said mandrel frame, and a cog wheel provided with a cam and means for actuating said shifting means whereby said wheel engages one of said pins to swing said mandrel frame out of filing position, on further turning actuates said shifting means, and on further turning engages the other pin to swing said mandrel frame back into position for filing the saws.

In testimony whereof, I set my hand in the presence of two witnesses, this 8th day of August, 1907.

FRANK A. BLAIN.
